E. A. L. ROBERTS.
SAND PUMP.

No. 65,121.

Patented May 28, 1867.

United States Patent Office.

E. A. L. ROBERTS, OF TITUSVILLE, PENNSYLVANIA

Letters Patent No. 65,121, dated May 28, 1867.

IMPROVEMENT IN SAND-PUMPS.

The Schedule referred to in these Letters Patent and making part of the same.

TO ALL WHOM IT MAY CONCERN:

Be it known that I, E. A. L. ROBERTS, of the city of Titusville, county of Crawford, and State of Pennsylvania, have invented a certain new and improved Sand-Pump; and I do hereby declare that the following is a full, clear, and exact description thereof, reference being had to the accompanying drawings, in which similar letters represent similar parts in all the views.

The nature of my invention consists in so constructing a sand-pump (for removing sand and sediment from oil and other deep wells) that, first, the sand and sediment shall be drawn or forced into the pump by means of atmospheric or fluid pressure, or both, at the bottom of the well; and, second, that the sand brought up by the pump can be emptied or removed from it without inverting it, or detaching it from the sand-rope, thereby saving much time, and at the same time doing the work more effectually than can be done by any pump now known or used. To accomplish this result, I construct the pump as shown in the annexed drawings, in which—

Figure 1 represents an outside view or elevation of my improved pump.

Figure 2, a vertical section of the same, showing my improved bottom valve as applied to my pump.

Figure 3 represents a vertical section of the same, with an ordinary ball-valve.

Figure 4 is a top view of the pump.

Figure 5, a bottom view of the plunger or upper valve of the same.

Figure 6, a bottom view of the pump, showing the cross-bar in which my improved valve works.

My pump consists substantially of the cylinder or barrel *c*, surmounted by the perforated cap *i*, and provided with an improved valve, *l*, at the lower end, the piston *h*, provided with a plunger and valve, working inside of the barrel *C*.

When the pump is lowered into the well, the bolt *k*, extending from the bottom of the valve *l*, striking the sediment, or the bottom of the well, opens the valve, and keeps it open, until the pump is raised; or when a ball or other valve is used, the suction of the plunger, when raised, will lift the valve from its seat, and allow the sediment to pass into the pump. Upon giving the sand-rope sufficient "slack," the plunger descends to the bottom of the pump, and upon lifting the piston and plunger, by means of the sand-rope, the sand and sediment enter the bottom of the pump and fill it, the air or fluid in the pump above the plunger passing out through the holes *s s* in the cap *i*. The plunger striking against the under side of the cap *i*, raises the pump, with its contents, to the top of the well, when, in order to empty the pump, it is simply necessary to lower it, when in a vertical position, upon the floor of the derrick or other convenient place; the projecting bolt *k*, striking the floor, raises the valve *l*; the plunger, being at the top of the pump, the air passes through the holes *s s* provided for that purpose, and the sand and sediment pass out at the bottom of the pump, the fluid in the upper part of the barrel passing out after the sediment, and thoroughly cleansing every part of the pump, thus rendering the pump ready for use again, the whole operation of cleansing the pump being done without inverting it or removing it from the sand-rope, which is a great advantage over any other pump known, and especially when a very long pump is used. At the lower end of the barrel I provide the side openings *q q*, through which the sediment passes when the pump rests on the bottom of the well.

In case a ball or other valve is used, it is only necessary to provide and insert a pin, *k*, fig. 3, in the floor of the derrick, or other convenient place, and by setting over and lowering the pump on it, the pin raises the ball or other valve, and allows the sediment to pass out. Other forms of valve can be used, and opened by the same or other means.

1. I claim the combination, substantially as and for the purposes herein set forth and described, of a tube, piston, and foot-valve, the latter being opened for the purpose of discharging the contents of the pump, by means of the stem *k*, or its equivalent, whether attached to, or separate from the valve.

2. The perforations *s*, as arranged in relation to said sand-pump, for the purposes herein set forth.

Dated at Titusville, Pennsylvania, this fourth day of February, A. D. 1867.

E. A. L. ROBERTS.

Witnesses:

F. L. SEELY,

ANDREW B. HOWLAND.
